OIL BURNER

Oscar J. Appel, Paterson, N. J.

Application March 31, 1934, Serial No. 718,352

7 Claims. (Cl. 158—77)

My present invention relates to oil burners of the vertical rotary type wherein a rotary burner head or sprayer which is disposed centrally of a hearth within a fire-box is adapted to spray liquid fuel and air outwardly toward a flame wall or fire-ring where combustion takes place, and aims to provide certain improvements therein.

Among the objects of my invention are the following: to provide a device of the type described, which, together with all of its associated parts, can be easily installed, and which, should necessity require, can be readily inspected or repaired; to provide such device wherein the burner head unit is hingedly mounted and can be swung down into the ash pit for inspection and repair without reaching into a hot fire-box; to make such device with all the parts which in use are exposed to the heat of the flame, capable of withstanding such heat for longer periods and of low replacement cost; to provide such device wherein the burner head and hearth fire-pot are formed as a compact, complete unit whereby the shipping and installation thereof are facilitated, and to generally improve the efficiency and reduce the cost of such devices.

The foregoing and other objects of my invention will be better understood from the detailed description which follows, when considered in conjunction with the accompanying drawings, wherein I have shown a preferred embodiment of my invention and wherein:—

Figure 1 is a diametrical section through an oil burning apparatus embodying my invention, certain parts thereof being shown in elevation.

Fig. 2 is a fractional section partly in elevation showing a manner of mounting the burner head upon a motor shaft.

Fig. 3 is a section taken substantially along the plane of the line 3—3 of Fig. 2.

Fig. 4 is an end view on an enlarged scale of one of the oil discharge tubes and its impeller blade.

Fig. 5 is a top plan view with parts broken away, of the apparatus taken from within the fire-box, the encircling wall of which is shown in section.

Fig. 6 is a section taken substantially along the plane of the line 6—6 of Fig. 1.

Fig. 7 is a section taken substantially along the plane of the line 7—7 of Fig. 1.

Referring to the drawings, let A indicate a water leg of a vertical boiler having an inner wall a defining a fire-box, centrally of which is disposed an oil burner unit B having a rotatable burner head C adapted to be rotated at a high

rate of speed by any suitable means, such as an electric motor D. Preferably the burner head C is mounted to extend above a hearth or bottom wall E which closes the lower end of the fire-box and extends from the water leg of the boiler to the oil burner unit. The hearth E may be suitably supported upon boiler grate lugs F or upon burner legs G which are provided with adjustable screws g and lock nuts 2g whereby the hearth may be properly leveled and given its desired elevation.

The oil burner unit B consists of a main casing having a cylindrical wall b formed with circumferentially spaced openings 2b, the top of said casing being formed with an outwardly-extending flange 3b, and the bottom being provided with a wall 4b which is centrally apertured and formed with an upstanding flange 5b. The bottom wall 4b acts as a supporting plate for the motor D which is secured to said wall by cap-screws 6b which extend through ears d on the motor housing adjacent its top. Between the top of the motor housing and the wall 4b when said parts are connected together I insert a ring of asbestos or other heat insulating material 2d and provide in said ring a slot or clearance space for the oil supply pipe H, the inner end of which extends up through the central opening in the bottom wall 4b and is curved outwardly and downwardly, as best shown in Fig. 1, to provide an oil delivery nozzle h. Secured to the inner face of the wall b in substantially abutting relation thereto and covering the openings 2b therein is a supplemental wall or metal strip J, which, at the places coincident with the openings 2b in the wall, has disk-like elements formed by cutting through the wall J for the greater part of circles to provide shutter-like elements j which can be bent inwardly away from the wall b to vary the degree of the openings through the wall b and thereby control the supply of air passing therethrough into the burner. To facilitate the manipulation of the disk-like shutters j they may each be centrally provided with an opening 2j into which a suitable tool or key may be inserted for adjustment of said shutters from the exterior of the casing B.

Above the main casing and secured to the flange 3b thereof is a burner casing cover having a cylindrical wall 1b, a bottom outwardly-extending flange 8b overlying the flange 3b and a top inwardly-directed flange 9b. Between the flanges 3b and 8b there is preferably provided an air gap 10b for reducing the heat transference from the casing cover to the main casing and

extending into the main casing in concentric spaced relation to the cylindrical wall thereof is a plate K which terminates in spaced relation to the bottom wall of the main casing, said plate 5 K being adapted to reduce air and combustion noises and in effect constitute a silencer for the burner.

Extending centrally upwardly through the main casing and casing cover is a motor shaft 10 3d, which, at its outer end 4d is tapered, and for a portion inwardly of said end is of somewhat reduced diameter, beyond which a portion of its length is formed with diametrically opposed axial grooves 5d, the said end of the shaft 15 being adapted to support and centralize the burner head C in a manner which will be presently described. Below said supporting end and extending to a point close to the top of the motor, the shaft is preferably hollow and formed with 20 transverse perforations 6d for reducing the heat conductivity of said shaft and for promoting the heat transfer therefrom to the air being supplied to the burner. If desired, this heat transfer can be increased by fitting into the openings 25 6d hollow radiating tubes or projections 7d.

The burner head C or impeller assembly consists of an open oil receiving cup L, the bottom of which is turned or curled inwardly to provide an oil receiving trough 1. The cup L has secured thereto within the top thereof a bracket 21, which in turn, is connected to a spider formed by a pair of crossed brackets, each of which has two pairs of parallel legs 4l and 5l, the legs 4l terminating at their tops in outwardly-extending 30 arms 6l which are secured to a cover plate 7l, and the upper portions of the legs 5l being connected together and centrally apertured to receive therethrough the end 4d of the motor shaft. For centering the oil receiving cup and impeller upon the motor shaft 3d, the bracket 21 has a central opening therethrough for accommodating the motor shaft 3d and extending into said opening are a pair of inwardly and upwardly-directed lips 8l for engagement within 35 the grooves 5d in the motor shaft for providing a driving connection between said parts, as shown in Figs. 2 and 3. As the bottom open end of the cup L must clear the oil supply nozzle h when mounting the burner head C upon the motor shaft 3d, the opening in the bracket member 21 which is provided with the lips 8l, is formed with an elongated offset opening 9l, as best 40 shown in Fig. 3. In this connection it may be stated that the manner of mounting the burner head upon the motor shaft and for centering the same is substantially the same as disclosed in my co-pending application, Serial No. 542,295, filed June 5, 1931.

Extending upwardly and outwardly from the 45 top of the cup L are a plurality of oil ejector nozzles M which are each formed with a longitudinal slot m on the trailing side thereof for the exit of air therefrom, said nozzles being of small bore and of substantially spiral cross-section and adapted to concentrate the discharge of fuel from the path provided by the ejector nozzles. The outer ends of the ejector nozzles preferably extend in a substantially horizontal plane so that upon rotation of said nozzles at a high 50 rate of speed they will centrifugally discharge oil from the cup L outwardly toward the wall a of the fire-box. To promote the atomization of said oil and produce an efficient combustible mixture thereof with air for ignition at the fire-ring 55 within the fire-box, I preferably mount an im-

peller or fan blade N at the end of each of the nozzles M so as to be rotatable therewith, and preferably dispose said fan blade in the central vertical plane of the discharge end of said nozzle. Each of the fan blades N has a transverse opening n extending substantially centrally therethrough and preferably said opening traverses the end of the nozzle, which latter may terminate within said opening, as best shown in Fig. 1, so as to allow a portion of the air which is gathered, compressed and directed outwardly by the fan blade as it revolves to impact the oil being projected from the nozzles to cause atomization of said oil, the said action being somewhat analogous to that of a Venturi tube. As herein shown, the blades N are secured to and carried by the nozzles M, but it will be apparent that if desired, said blades can equally well be secured to the cover plate 7l. The cover plate 7l has downwardly-extending peripheral arms 10l disposed between the fan blades N so as to promote the fan action of the burner head.

The hearth E is disposed where normally the top of the grates would be in a coal burning furnace, and said hearth may be supported either 25 upon the lugs F, or where this is not practicable or desirable, other independent supporting means such as the legs G may be availed of. As herein shown, the hearth E consists of a hearth partition or extension plate e seating upon the 30 lugs F, a centrally split burner frame or hearth partition O mounted upon the plate e, hearth insulation material 3e disposed over the plate e and burner frame O, a base plate 4e which may be formed integral with a fire-ring wall 5e extending upwardly from the hearth and spaced inwardly adjacent the fire-box wall, a circumferential series of upstanding air deflector ribs 6e mounted at the base of the fire-ring and spaced inwardly therefrom, and a perforated 35 refractory wall 7e, which, with the wall 5e, and wall 8e provides a hollow flame retaining chamber. Preferably the two sections o of the burner frame are interconnected by hinges 2o located on the under side of said plates, as best shown in Fig. 5, the hinged connection between said parts o being such as to permit the two sections to fold up with the under sides thereof facing each other. When opened up and disposed upon the partition plate e or supported upon the connecting members 3g of the legs G, the burner frame sections o become a flat ring.

The burner frame O has a central opening through which the burner head and a part of the burner casing extend and it is preferable that said burner frame should serve as the supporting means for the oil burner unit. Accordingly, one of the burner frame sections o is provided on its under side with a pair of depending lugs 3o which support a hinge pin 4o. The burner 40 unit B is provided with a pair of hooks 11b preferably supported by main casing thereof, said hooks being adapted to engage around the hinge pin 4o, as best shown in Figs. 1 and 6. To hold the burner unit in its upright position in engagement with the burner frame O, any suitable cooperating securing means may be provided on said burner frame and burner unit at a point diametrically opposite to the hinge. As herein shown, I prefer to hold said parts in assembled 45 relation by providing a bolt 5o extending downwardly from the burner frame and by forming a slot in the flanges 3b and 8b through which said bolt may pass, and holding said burner head in position through the medium of a single means 50 55 60 65 70 75 80 85 90 95 100 105 110 115 120 125 130 135 140 145 150 155 160 165 170 175 180 185 190 195 200

such as a removable nut 60 engaging said bolt below said flanges. It will thus be seen that by removing the nut 60, the burner unit as a whole will swing downwardly into the ash pit below the hearth around the hinge pin 40, in which position it may be inspected or slight adjustments made. Should the unit require further detailed inspection or repair it may be completely disengaged from the hinge pin by lifting the hooks therefrom. To insulate the burner casing from the hearth, a ring P of asbestos or other insulating material may be disposed between the burner frame O and the flange 8b.

While the oil burner unit disclosed may be used with various types or constructions of fire-rings mounted upon the hearth, I prefer to use a fire-ring construction as shown and which comprises spaced upstanding refractory walls 5e and 7e, the tops of which are bridged by a wall 8e, which, 20 like the inner wall 7e, may be perforated, and I prefer to provide the inner of said refractory walls with deflector means R which preferably extend inwardly and downwardly from adjacent the top of the wall 7e for directing the combustible fuel mixture which rises up in front of the wall 7e through the openings 9e in said wall into the chamber of the fire-ring. I also prefer to provide deflector means 10e at the rear of the wall 7e, said deflector means being preferably 30 formed by partially cutting through disks from the wall 7e in the course of perforating said wall and bending said disks backwardly, in which position they will deflect the blasts of air which pass through said perforations 9e and increase 35 turbulence within the annular chamber and thereby prevent said air currents from setting up a sufficient draft to carry away the flame.

A pilot or other ignition means (not shown) may be provided near the inner face of the fire-ring at the hearth level thereof or within the chamber formed by the walls of the fire-ring, for igniting the combustible mixture of fuel and air upon reaching the fire-ring.

With an oil burner construction and attendant parts as hereinbefore described, it will be appreciated that it is possible to ship in compact form a burner that may be applied to a heating plant by unskilled labor and in less time than has been heretofore required for analogous installations with specially trained labor. The burner frame or hearth partition O being of a two-piece hinged construction needs only to be folded, slipped into the fire-box, and unfolded so as to rest upon the grate lugs, or burner legs where lugs are not available for supporting the burner frame. The insulation 3e in sheet or cement form can next be applied as part of the partition or hearth. In the case of a round or almost square boiler only two split metal sections of the flame ring 4e—5e need then be centrally placed upon the partition. Perforated metal wall 7e is then placed in position, and after sealing the outer edges of the partition or any other point from which possible air leaks between it and the inner surface 65 of the fire-box can take place, the burner unit may be hooked into position by the novel hinge arrangement described, and swung and fastened into place. With the connecting of the oil line, the electric current and proper automatic controls and the ignition means, the burner is ready for operation. This burner structure combination, it will be apparent, simplifies installation of the burner by eliminating complicated hearth constructions, and because of the rigid uniform 70 structure of both the burner mechanism and the

partition or burner frame, it is rarely necessary to level the burner within the fire-box since the burner mechanism and the flame ring automatically line up. It will thus be appreciated that the necessity for reaching into a hot fire-box to remove the oil and air distributing head has been eliminated, for by simply removing one lock nut and disconnecting the oil line, the burner mechanism can be swung down into the ash pit section of the furnace, whereupon the distributing head may be removed, or, if any part needs closer inspection, repairs or replacement, the whole burner mechanism may be unhooked as hereinbefore described. The burner construction being of a unitary character makes quick interchange 15 of units possible so that uninterrupted heat can be maintained should repairs in the unit become necessary.

While I have shown and described a preferred construction of my invention and the manner in which the same may be operated, it is to be understood that I do not wish to be limited to the details of construction disclosed, since modifications thereof may be resorted to without departing from the spirit of the invention. 25

What I claim is:

1. An oil burner comprising an ejector nozzle mounted for rotation in a path non-coincident with its own axis for throwing off oil centrifugally, and an impeller blade carried by and movable with said ejector nozzle, said blade extending in substantially the axial plane of the nozzle at an angle to the path of rotation of the nozzle end. 30

2. An oil burner comprising an ejector nozzle 35 mounted for rotation in a path non-coincident with its own axis for throwing off oil centrifugally, and an impeller blade movable with said ejector nozzle, said blade extending in substantially the axial plane of the ejector end of said 40 nozzle at an angle to the path of rotation of the nozzle end and said blade having an opening therethrough beyond the ejector end of said nozzle.

3. An oil burner comprising an ejector nozzle 45 mounted for rotation in a path non-coincident with its own axis for throwing off oil centrifugally, and an impeller blade for discharging air, said blade being carried by and movable with said ejector nozzle and having a transverse opening therethrough adjacent said nozzle end for creating a flow of air transversely to the nozzle end upon rotation of the nozzle. 50

4. An oil burner comprising an ejector nozzle mounted for rotation in a path non-coincident 55 with its own axis for centrifugally discharging oil, said nozzle being slotted longitudinally on the trailing side thereof for the exit of air therefrom, an impeller blade for discharging air, said blade being carried by said nozzle, and means for rotating the nozzle and the blade as a unit in a circular path.

5. An oil burner comprising, in combination, a fire-box, a vertical rotary oil burner unit disposed centrally thereof and a hearth closing the bottom 65 of the fire-box and extending to the burner unit, said burner unit comprising a head which extends above said hearth into the fire-box, ejector nozzles for centrifugally discharging oil therefrom, said nozzles being slotted longitudinally on the 70 trailing sides thereof for the exit of air therefrom, a cover plate disposed above said nozzles but spaced therefrom and impeller blades movable with said cover plate and said ejector nozzles.

6. A liquid fuel burner comprising a rotary 75

3. head, ejector nozzles attached to said head and adapted to centrifugally project fuel therefrom, the discharge ends of said nozzles being of small bore of substantially spiral cross-section, and an impeller blade fixed to the outer end of each nozzle and rotatable therewith.

7. A liquid fuel burner comprising a rotary head, ejector nozzles attached to said head and adapted to centrifugally project fuel therefrom,

and impeller blades rotatable with the rotary head and disposed in substantially the axial planes of the ejector nozzles, at an angle to the path of rotation of the nozzle ends, said blades each having a port for creating a transverse current of air adjacent the discharge end of an ejector nozzle during rotation of the head. 5

OSCAR J. APPEL.
